E. SWANSON,
KNOCKDOWN HEN'S NEST,
APPLICATION FILED JULY 31, 1919.

Patented Aug. 31, 1920.

Inventor.

Edward Swanson.

by *Rudolph G. Holt*
Atty.

UNITED STATES PATENT OFFICE.

EDWARD SWANSON, OF SHEFFIELD, ILLINOIS.

KNOCKDOWN HEN'S NEST.

1,351,308.

Specification of Letters Patent. Patented Aug. 31, 1920.

Application filed July 31, 1919. Serial No. 314,460.

To all whom it may concern:

Be it known that I, EDWARD SWANSON, citizen of the United States, residing at Sheffield, in the county of Bureau and State of Illinois, have invented certain new and useful Improvements in Knockdown Hens' Nests; and I do hereby declare that the following is a full, clear, and exact description of the invention, such as will enable others skilled in the art to which it appertains to make and use the same.

This invention relates to new and useful improvements in hens' nests and has for its particular object to provide means whereby the structure may be readily knocked down for purposes of packing and shipping in small spaces and which, when assembled, may be suspended from suitable supports engaging the rear wall thereof without danger of any portion of the nest becoming loose.

A further object of the invention is to provide a nest of the character defined wherein the top wall may be moved so as to confine a setting hen in the nest, if desired, and at the same time prevent the entrance of other hens to the nest to disturb the setting hen.

The present invention relates more particularly to certain improvements in the constructions of the nest described and claimed in my co-pending application for Letters Patent, Serial Number 189,556, filed February 4, 1917, allowed May 29th, 1919, which has since become Patent No. 1,315,432, issued Sept. 9, 1919.

The invention consists in the features of construction and combinations of parts hereinafter fully described and claimed and illustrated in the accompanying drawings in which:

Figure 1 is a perspective view of a hen's nest constructed in accordance with the invention, certain parts being broken away to disclose details of construction.

Fig. 2 is a plan section of the nest.

Fig. 3 is a vertical longitudinal section of the same, partly broken away.

The said structure is preferably made of sheet metal of suitable character and comprises a bottom element 1, end walls 2 and 3, side walls 4 and a top wall 10. The said end and side walls are provided along their vertical edges with telescopically interengaging formations of any suitable nature whereby said walls may be suitably engaged

with each other against movement in any direction except longitudinally of the corners thereof and whereby said walls are caused to normally extend at right angles to each other. The front wall 2 has a substantially V-shaped upper edge portion and is provided along its straight bottom edge with an outwardly extending edge 5. The side walls are provided along their lower edges with inwardly extending substantially U-shaped flanges 6 which present opposed channels in which the side edges of the bottom plate 1 are received so that said bottom plate may be slid into place underneath the flange 5 of the front wall. The rear wall is provided along its lower edge with an outwardly extending U-shaped or channeled flange the mouth of which flange 7 is adapted to receive the rear edge of the bottom wall, and this flange abuts against the lower ends of the flanges at the rear edges of the side walls thus requiring the said rear wall to be moved to its proper position relatively to the side walls by inserting the same in an upward direction. Thus when the bottom wall is engaged in the channel of the flange 7 of the rear wall the latter will be held against vertical movement relatively to the side walls. The front edge of the bottom wall terminates in a substantially tubular portion 8 providing a slot opposing the front wall into which the flange 5 of the front wall 2 is adapted to project when the rear edge of the bottom wall enters the channel of the flange 7 of the rear wall thus holding the front wall against vertical movement relatively to the side walls.

The side walls are provided along their upper edges with outwardly extending overturned flanges 9 which provide channels having downwardly extending mouths. The said upper edges of the side walls are inclined, (the rear wall being of greater length than the front wall) to accord with the relative elevations of the said top edges of the said front and rear walls. A cover element 10 which is provided with inwardly extending overturned flanges 11, the channels which are adapted to receive the free edges of the flanges 9 of the side walls is slideable on the upper edges of said side walls and may be moved to any desired position between the front and rear edges of said side walls, though normally said cover member will lie so that its rear edge is flush to the rear wall of the nest, thus providing

an opening at the front of the nest through which the hen may enter the same. Said cover is adapted to be moved to a more forward position to partially close the entrance opening to the nest for the purpose of confining setting hens in the same and preventing other hens from bothering the setting hen.

In the upper end portion of the rear wall 10 3 is a plurality of openings 12 through which hooks or other suitable projections on a wall of the hen-house may project so that the entire nest becomes suspended from the same. Obviously this renders necessary 15 the holding of the rear wall against vertical movement or sliding out of place under influence of the weight of the nest and its contents, this being accomplished by the engaging of the flange 7 at the lower end 20 of the rear wall with the rear edge flanges of the side walls.

While I have shown the preferred embodiment of the invention in the accompanying drawings, it will be understood, of course, 25 that said embodiment may be changed and varied in details without departing from the invention as defined in the appended claims.

I claim as my invention:

1. A hen's nest comprising a rectangular 30 receptacle having a cover element adapted to partially cover the same, and a slidable connection between said cover and the side walls of the receptacle for permitting said cover to be moved to position to provide 35 two openings in the top of the receptacle of smaller than sufficient dimensions to permit entrance or exit of a hen.

2. A knock-down hen's nest comprising a rectangular receptacle composed of peripheral walls telescopically engaged with each other along their vertical edges, channeled flanges at the lower edges of the side and rear walls thereof, said flange of said rear wall adapted to abut against the lower ends of the channeled flanges at the rear 45 edges of the side walls, a bottom plate adapted to engage along its side and rear edges in the channels of the flanges along the lower edges of the side and rear walls, inter-engaging formations along the front 50 edge of the bottom member and the lower end of the front wall, whereby said bottom wall locks the peripheral walls of the receptacle against relative movement, said rear wall equipped with means for suspending 55 the nest from a wall of a hen-house.

3. A knock-down hen's nest comprising a rectangular receptacle having peripheral walls telescopically engaged with each other, a removable bottom for said receptacle having 60 interlocking engagement with the peripheral walls of the receptacle whereby the latter are locked against movement relatively to each other, the rear wall being equipped with means for suspending the receptacle from a wall of a hen-house and the rear and side walls being equipped with inter-engaging means acting independently 65 of their engagement with the bottom wall for preventing relative vertical movement of 70 said rear and side walls in one direction by gravity when the rear wall is suspended from a wall.

EDWARD SWANSON.
